UNITED STATES PATENT OFFICE.

ALFRED CHRISTENSEN AND CHRIST OVERGAARD, OF COULTER, IOWA.

PERMUTATION-VALVE.

1,168,163.

Specification of Letters Patent. Patented Jan. 11, 1916.

Application filed June 14, 1915. Serial No. 34,088.

To all whom it may concern:

Be it known that we, ALFRED CHRISTENSEN and CHRIST OVERGAARD, citizens of Denmark, residing at Coulter, in the county of 5 Franklin and State of Iowa, have invented certain new and useful Improvements in Permutation-Valves, of which the following is a specification.

The object of the present invention is to 10 provide locking means in the form of a fuel cut-off for safe-guarding unauthorized usage of a motor vehicle, said means in the preferred embodiment consisting of a permutationally operated device interposed in 15 the fuel line, so as to interrupt at will the passage of fuel from the supply tank to the engine, necessitating acquaintance with the combination before again rendering the vehicle operative.

20 More specifically the invention comprises spaced supports to which the fuel conduit connects and intermediate which are rotatably mounted a plurality of permutation cylinders, said cylinders having passages 25 therethrough adapted only to register with each other and with the fuel line upon disposition of the cylinders in a predetermined relation as may be indicated by indicia thereon.

30 It is further contemplated to provide the members with suitable interlocking tongue and groove connections designed for the purpose of preventing leakage of the liquid.

For a full understanding of the present 35 invention, reference is to be had to the following description and the accompanying drawings, in which:

Figure 1 is a plan view of a device constructed in accordance with our invention. 40 Fig. 2 is a longitudinal section therethrough, the fuel line connecting with the device being omitted. Fig. 3 is an end elevation. Fig. 4 is a transverse sectional view taken about on the line 4—4 of Fig. 1; and Fig. 45 5 is an end elevation of one of the permutation cylinders employed in this invention.

Throughout the following detail description, and on the several figures of the drawings, similar parts are referred to by like 50 reference characters.

It may be here stated that the invention is illustrated in the drawings in its simplest embodiment, and we desire it to be understood that the mechanism may be made more complicated so as to render it more difficult to carry out its objects of establishing

continuous communication in the fuel line, as by utilizing a greater number of permutation members, only a pair of which are disclosed by the present drawing.

In carrying out the invention, it is contemplated to attach the device on the dash or at any other suitable location of a motor vehicle, which support is indicated in the drawing by the numeral 1, it being desirable, of course, that the valve construction or cut-off be located at a convenient point for access. To the support 1 are connected by means of fastening members 2, spaced supporting or end elements 3 of suitable size and configuration. These supporting members are formed with transverse passages 4 preferably in alinement with each other and the fuel line or conduit 5 in which the device is interposed leads to the passage 4 of one of the supports and from the corresponding passage of the other support. The spaced ends of the conduit 5 may have threaded connection with the supporting members 3 or be otherwise attached so as to prevent leakage of the fluid at these points. Upon the bolt 6 adjustably connecting the spaced supports 3 together and intermediate said supports are rotatably mounted a plurality of permutation cylinders, designated in the drawing 7, 7'. These members are preferably of similar form and construction having corresponding transverse passages 8, 8' respectively formed therein, and so disposed as to be capable of alinement or registry with each other and with the passages 4 of the respective spaced supports 3. When in such alined position, it will be apparent that the fuel may readily pass from the supply tank (not shown) to the motor or engine construction (not shown).

Obviously a movement or rotation of one or both of the permutation cylinders 7, 7' a distance equivalent to the diameter of the fuel line passage will interrupt the supply of fuel and necessarily prevent operation of the motor to which said fuel is supplied. In order primarily to prevent leakage of the fuel from the passages through these parts each permutation member is formed at one side with annular concentric grooves 9 and at its other side with annular tongues or projections 10 which seat, of course, in the contiguous grooved face of the adjacent element. The spaced supports 3 are likewise provided with annular tongues and projections to provide the proper interlock-

ing arrangement with the adjacent permutation cylinder, all as most clearly illustrated in Fig. 2 of the drawing. Obviously a very tight and leak-proof connection between the elements is thus provided and wear of the parts which may be incident to the use of the device as well as undesired play between the cylinders may be eliminated by the adjustment of the nuts 6' on the axial bolt 6 connecting the members together. The nuts 6' may be screwed sufficiently tight, if desired, to lock the members 7, 7' from rotation entirely as when it is unnecessary to provide against unauthorized tampering with the device. In order that the proper registry of the passages through these different parts may be accomplished, each of the cylinders is provided with certain indicia, such as space marks and numerals indicated generally at 11 which operate with arrows or similar designations 12 located on the supports 3. The proper combination to obtain such registry, of course, is supposed to be known only to the operator of the vehicle and each device built in accordance with this arrangement may be provided with a different permutation combination so as to make difficult to those unfamiliar with said combination, the proper setting of the cylinders to establish communication of the supply tank with the engine as hereinbefore set forth.

Having thus described the invention, what we claim as new is:

35. 1. In a device of the class described adapted for interposition in the fuel line for a motor vehicle or the like, the combination with spaced supports to and from which said fuel line leads, rotatable cylinders intermediate said supports, said cylinders having communicating means formed at corresponding distances from the axial center of the cylinders and adapted for registry with the fuel line upon disposition of the cylinders in a predetermined relation to each other and to said supports the fuel line being

likewise disposed with respect to the axial center whereby to provide a continuous, aligned fuel passage through the device, and an axial support for said cylinders connecting the supports together and adjustable to take up wear and control operation of the cylinders.

2. In a device of the class described adapted for interposition in the fuel line for a motor vehicle or the like, the combination with spaced supports having aligned fuel passages to and from which said fuel line leads, rotatable cylinders intermediate said supports, said cylinders having communicating means adapted for registry in the same plane as the passages of the fuel line upon disposition of the cylinders in a predetermined relation to each other and to said supports, an axial support for said cylinders connecting the spaced members aforesaid together, and interlocking means between the faces of the cylinders and supports for preventing leakage of the fuel.

3. In a device of the class described, the combination of spaced supporting elements adapted to be interposed in a fuel supply line, means for holding said supports in spaced relation, permutation cylinders rotatably mounted between said spaced supports, passages formed in said supports and cylinders adapted to be brought into registry to establish continuous communication in a horizontal plane through the fuel line upon disposition of said cylinders in predetermined relation to each other and to said supports, an adjustable axial support for said cylinders, said cylinders and supports being formed with tongue and groove interlocking connections for preventing leakage of the fuel, and means to indicate the registered position of the passages hereinbefore mentioned.

In testimony whereof we affix our signatures.

ALFRED CHRISTENSEN.
CHRIST OVERGAARD.
